CHAIR

Luther A. Smith, Birmingham, Ala., assignor to Southern Household Products Company, Inc., a corporation of Delaware

Application May 25, 1949, Serial No. 2,871

Term of patent 3½ years

(Cl. D15—1)

To all whom it may concern:

Be it known that I, Luther A. Smith, a citizen of the United States, residing at Birmingham, county of Jefferson, State of Alabama, have invented a new, original, and ornamental Design for a Chair, of which the following is a specification, reference being made to the accompanying drawings forming a part thereof.

Fig. 1 is a perspective view of the chair showing my new design;

Fig. 2 is a side elevational view of the same;

Fig. 3 is a plan view of the same;

Fig. 4 is a front elevational view of the same;
and

Fig. 5 is a rear elevational view of the same.

I claim:

The ornamental design for a chair, substantially as shown.

LUTHER A. SMITH.
